UNITED STATES PATENT OFFICE.

JOHN SAFAR, OF CHICAGO, ILLINOIS.

DESIGN FOR COAT AND HAT RACK.

Application filed December 15, 1923. Serial No. 8,060. Term of patent 7 years.

To all whom it may concern:

Be it known that I, JOHN SAFAR, a citizen of Hungary, residing at Chicago, in the county of Cook and State of Illinois, have invented a new, original, and ornamental Design for a Coat and Hat Rack, of which the following is a specification, reference being had to the accompanying drawing, forming part thereof.

The drawing is a perspective view.

I claim:

The ornamental design for a coat and hat rack, as shown.

JOHN SAFAR.
